Primary Examiner — Prabhakar Deshmukh(74) *Attorney, Agent, or Firm* — Nixon & Vanderhye, P.C.(57) **CLAIM**

The ornamental design for a wireless transmitter/receiver, as shown and described.

DESCRIPTION

FIG. 1 is a front, left and bottom perspective view of a wireless transmitter/receiver showing my new design;

FIG. 2 is a rear, right and top perspective view thereof;

FIG. 3 is a front view thereof;

FIG. 4 is a rear view thereof;

FIG. 5 is a top plan view thereof;

FIG. 6 is a bottom plan view thereof; and

FIG. 7 is a left side view;

FIG. 8 is a right side view;

FIG. 9 is a front, left and bottom perspective view of the wireless transmitter/receiver in a lid-opened state;

FIG. 10 is a rear, right and top perspective view thereof;

FIG. 11 is a front view thereof;

FIG. 12 is a rear view thereof;

FIG. 13 is a top plan view thereof;

FIG. 14 is a bottom plan view thereof; and

FIG. 15 is a left side view; and,

FIG. 16 is a right side view.
